UNITED STATES PATENT OFFICE

110,410

DESIGN FOR A TEXTILE FABRIC

William Cohen, New York, N. Y.

Application May 13, 1938, Serial No. 77,149

Term of patent 3½ years

To all whom it may concern:

Be it known that I, William Cohen, a citizen of the United States of America, residing in New York city, in the Borough of Manhattan, county and State of New York, have invented a new, original, and ornamental Design for a Textile Fabric, of which the following is a specification, reference being had to the accompanying drawing, forming part thereof, wherein,

The figure is an enlarged plan view of a piece of textile fabric showing my new design.

The design is of uniform color and comprises a series of ribs separated by narrow grooves which appear to be darker in color, and a series of double chain-like threads crossing the ribs and grooves at right angles as shown.

I claim:

The ornamental design for a textile fabric, substantially as shown and described.

WILLIAM COHEN.
